UNITED STATES PATENT OFFICE.

REUBEN B. BENJAMIN, OF CHICAGO, AND CHESTER E. WARNER, OF BERWYN, ILLINOIS,
ASSIGNORS TO BENJAMIN ELECTRIC MANUFACTURING COMPANY, OF CHICAGO,
ILLINOIS, A CORPORATION OF ILLINOIS.

DESIGN FOR PLUG CLUSTER.

Application filed October 9, 1922. Serial No. 3,910. Term of patent 14 years.

To all whom it may concern:

Be it known that we, REUBEN B. BENJAMIN, a citizen of the United States, residing at Chicago, in the county of Cook and State of Illinois, and CHESTER E. WARNER, a citizen of the United States, residing at Berwyn, in the county of Cook and State of Illinois, have invented a new, original, and ornamental Design for Plug Cluster, of which the following is a specification, reference being had to the accompanying drawing, forming a part thereof.

Fig. 1 shows a side elevation of the plug cluster;

Fig. 2 shows an elevation of the plug cluster at right angles to that shown in Fig. 1.

We claim:

The ornamental design for plug cluster substantially as shown.

REUBEN B. BENJAMIN.
CHESTER E. WARNER.
